UNITED STATES PATENT OFFICE.

MORRIS G. ROSENTHAL, OF MENTOR, OHIO, AND ARTHUR ROSENTHAL, OF GRAND RAPIDS, MICHIGAN.

SEWING-MACHINE.

976,399.

Specification of Letters Patent. Patented Nov. 22, 1910.

Application filed February 28, 1910. Serial No. 546,569.

To all whom it may concern:

Be it known that we, MORRIS G. ROSENTHAL and ARTHUR ROSENTHAL, citizens of the United States, residing at Mentor, Lake 5 county, Ohio, and Grand Rapids, Kent county, Michigan, respectively, have invented certain new and useful Improvements in Sewing-Machines, of which the following is a specification.

10 Our invention relates to improvements in the attachments to sewing machines secured to us by Letters Patent of the United States numbered 948,345, issued February 8, 1910, and its objects are: First, as with our patent 15 hereinbefore mentioned, it is designed to sew labels, patches, trade mark slips &c., upon fabric, either in the piece or upon manufactured articles. Second, to remove the labor of operating the attachment from 20 the needle bar and placing it upon the shuttle shaft, thus greatly lessening the labor upon the needle bar crank and shaft, and the necessary labor of running the attachment. Third, to provide a means for 25 immediately stopping the machine when the label or other object has been fully sewed upon the fabric. Fourth, to provide a means whereby the length of the stitch may be readily adjusted. Fifth, to provide an attachment of the class named with which any 30 desired form of patch or label may be readily provided for without material change of parts, and, sixth, to provide a means whereby the first and last few stitches 35 in a label, patch or other attachment to the fabric, will overlap and thus double the strength of stitching at this point and avert the danger of the stitches raveling out or the label ripping off of the fabric.

40 We attain these objects by the mechanism illustrated in the accompanying drawing, in which—

Figure 1 is a front elevation of a sewing machine with our attachment in place. Fig. 45 2 is a plan of the same with the machine arm cut off on the line $x\ x$ of Fig. 1. Fig. 3 is a rear elevation of the machine with a part of our attachment in place. Fig. 4 is an end view of the base of our attachment 50 with the actuating arm cut off on the line $y\ y$ of Fig. 9 to show the manner of securing the pivot plate to the base. Fig. 5 is a per-

spective of the back acting pawl and its supporting slide. Fig. 6 is an elevation of our attachment looking to the left from the line 55 $z\ z$ of Fig. 2. Fig. 7 is a plan of the same. Fig. 8 is an elevation of the lever, plate and spring that holds the fabric and label when the label is being sewed on. Fig. 9 is a plan of the base and actuating arm showing the 60 gear wheel and form used for sewing on oblong labels. Fig. 10 is an enlarged perspective view of the fabric holding plate, arm, and adjustable foot, showing the lower edge of the foot serrated. Figs. 11 and 12 are enlarged 65 elevations of the oscillating lever that actuates the connecting rod that actuates the feed wheel. Fig. 13 is a sectional view on the line $x'\ x'$ of Fig. 11, and Figs. 14 and 15 show two forms of shifting rods 70 for shifting the driving belt.

Similar letters refer to similar parts throughout the several views.

In the construction and application of this attachment, we provide a base C that is designed to be firmly secured to the bed B of the sewing machine. To this base C is firmly secured two cleats, C', designed to receive and firmly hold the pivot plate C'' in such a manner that by loosening the screws or other devices with which they are secured to the base, the pivot plate may be readily slid sidewise to change the pivot point of the actuating arm D to increase or diminish the movement of the fabric holder composed of the 75 plate E, the clamping arm E' and the adjustable foot E'', and we, also, provide a 80 guard, as d', which forms a slot through which the actuating arm D may pass and work freely, either sidewise or lengthwise. 85 The fabric holder consists of a plate E that lies parallel with, and directly adjacent to the upper surface of the bed B. This plate is provided with standards e' to which is pivoted the lever e of the clamping plate E'. 90 The plate E is firmly secured to the actuating arm D, as at d, and has a bolt F pivotally secured to it and passing up through the clamping plate E', above which is a spring 95 F' and a regulating nut F'', by means of 100 which the pressure of the foot E'' is regulated. The foot E'' is to be made of the exact form that the line of stitching is to be made, and the opening e''' (see Fig. 10)

through the plate E', in which the foot is supported, must be made to practically correspond, though a considerable divergence may be made so that different forms of foot 5 may be used in the same opening providing the widths correspond. This foot is pivotally supported upon the plate E', as indicated at e'', so that it may readily adjust itself to the surface of the fabric b upon 10 which it bears. The lower edge of this foot may be made plain, or it may be serrated as shown in Fig. 4, as desired and as found most effectual in holding and carrying the fabric, indicated at b. The cord V attached 15 to the end of the arm e is designed to extend down to position, and to be connected or arranged that it may be acted upon by the foot of the operator to open and close the clamping device. That is, by drawing 20 downward upon the cord the back end or arm e, of the plate E' is drawn downward and the foot E'' is raised up off of the fabric b, and when the cord is released the spring F' will force the plate E' and the foot E'' 25 down solidly upon the fabric.

The actuating arm D, being pivoted at c and arranged to move freely in all directions beneath the guard d', is actuated as follows: In the back end of the arm D we 30 form an opening with inwardly projecting teeth D'' therein. This opening must be of a proper form to so carry the foot E'' in the proper directions and positions as to form the desired lines of sewing. To the back 35 end of the base C is attached a block or form, as D''', which must be of a proper form to cause the gear wheel D' to mesh firmly but freely with the teeth D'' as the arm is carried to the several positions necessary 40 for forming the desired line of stitching. The forms shown in Fig. 9 of our drawings are those now in use by us for forming an oblong line of stitching, as indicated by the foot E'' shown in Fig. 2, it being 45 understood that the movement given the foot by these forms is exactly right to cause the needle a to form the lines of stitching close to the inner surface of the foot. That is, the foot E'' has vertical walls that form 50 an opening that must conform to the shape of the label to be attached, and the fabric and label are so moved that a label of the desired form may be stitched to the fabric.

The shaft W, upon which the gear wheel 55 D' is mounted, passes upward and is supported by the arm G', and the ratchet wheel G is firmly mounted thereon, and to operate the shaft W to actuate the arm D, a connecting rod is pivotally attached to the arm i, 60 which is integral with the plate I, which plate is revolvably mounted upon the shaft W and has a pawl I' mounted thereon in position to engage the teeth on the periphery of

the wheel G so that said wheel, and with it the shaft W, will be moved the required distance with each alternate reciprocation of the connecting rod J, the pawl I' being made to alternately engage the teeth on the wheel G by a spring, as L'', as the needle approaches the end of its upward stroke. 65

The connecting rod J is actuated by the oscillating lever J', which is pivotally connected with the standard K, as at j', and is provided with a slot j by means of which the pivot point of the lever may be changed to 70 lengthen or shorten the stroke or movement of the upper end of this lever and, correspondingly, change the distance the pawl I' is made to travel and move the wheel G. The lower end of the lever J' is pivotally 75 connected with the slide M which is made to reciprocate by the cam L with each oscillation of the shuttle shaft L', or, in case of a rotary shaft, with each revolution of the shaft. It will be readily seen that by this 80 means, the changing of the pivot point at j' will correspondingly change the movement 85 of the wheel G. Thus, if the pivot point j' is placed well down toward the lower end of the slot j, the movement of the upper end of 90 the lever J' will be sufficient to cause the pawl I' to pass back over two or more teeth on the wheel G and thus move it much farther than if the pivot point is placed far enough up in the slot j to reduce the movement 95 of the pawl to a single tooth, and as the actuating arm D and the plate E, with its connections, are actuated by the movements of the wheel G, as hereinbefore more fully described, the length of the stitches in 100 the fabric is correspondingly changed.

In Fig. 13 we have shown the nut j' and the standard K and lever J', in section to more plainly show how the lever J' is pivoted to the standard. In this case the bearing j'' is made longer than the thickness of the standard so that with the washer j''' forced solidly against it by the nut j' the bearing may turn freely in the standard to allow the lever to be adjusted as desired. 105

We provide for shifting the driving belt and suddenly stopping the sewing machine by placing a loose pulley as O'', immediately adjacent to the tight, or driving pulley O'. We then place a reciprocating shaft, as S, 115 in bearings that are attached to, or are integral with the base B. In the construction of this shaft we prefer that the body portion of the shaft be made of a uniform size, as indicated in Figs. 2 and 3, and be provided with an annular groove, as s, which is designed to receive the latch U'' to hold the shaft to place where it will cause the belt R to act upon the driving pulley O' to drive the machine. Each end of this shaft 120 should be made so that it will slide freely

in its bearing, but cannot slide but a given distance. At one end of this shaft a coiled, or other suitable spring, as S'' , is so placed as to force the shaft, lengthwise, so that when the latch U'' is raised out of the groove s the shaft will be suddenly forced endwise and will, through the action of the shifter lever Q upon the belt R , force the belt off of the driving pulley O' and onto the loose pulley O'' , and thus stop the machine. As the machine would be likely to run several revolutions after the belt R has been shifted to the loose pulley, and as it is desirous that it should be stopped quickly, and so that the needle bar will always be on the up stroke, it is necessary to provide some auxiliary means of so stopping it, and for this purpose we have formed a shoulder o in the periphery of the fly wheel O , as indicated in Fig. 1, and have pivoted a lever P to the standard of the machine, as at p , in such a position that the upper end of said lever may be made to engage with, or be disengaged from the shoulder o and when made to engage said shoulder it will stop the machine instantly and always with the needle a up out of, and clear from the fabric b , or in the position indicated in Figs. 1 and 3. This lever is actuated to throw it into contact with the shoulder o by means of any available form of spring, as indicated at P' , or by any other available device; and to hold it out of contact with the shoulder and in position so that the machine may be run without interference therefrom, by the arm Q' which is shown as being integral with the shifting lever Q . The shifting lever Q is secured to the shaft S , as at q , in such a manner that it must be carried therewith, as the shaft is moved endwise in the operation of the machine while we prefer that the shifter Q and the arm Q' be made integral, as indicated in Figs. 1 and 14, the same results may be attained by the use of separate shifters, as indicated at Q'' and Q''' in Figs. 2 and 15.

The shaft S may be made of uniform size, if desired, and collars applied to prevent it from being forced too far by the spring S'' , but we prefer that the ends be made smaller, as shown at S' , to form the necessary shoulders for actuating and stopping the shaft, as they are less likely to be moved by the sudden movement of the shaft, and to allow the shaft to move too far at any time.

We provide for disconnecting the latch U'' from the groove s in the shaft S , by pivoting a plate U to the base B of the machine, as at u , in such a position that when it stands in its normal position the latch U'' may rest upon it and extend down nearly to the bottom of the groove s . This

plate is held in its normal position by any available form of spring, as W , attached at one end to the plate, as at w , and at the other end to the base, as at w' , and is actuated to throw it up to the position of its dotted lines, by means of a cable, or other flexible connecting element, as U' , attached at one end to the upper corner of the plate and at the other end to the arm e , in such a manner that when the arm e has moved far enough to the right, as indicated by its dotted lines in Fig. 3, the plate will be moved sufficiently to raise the latch out of the groove s and the spring S'' will force the shaft suddenly to the right, with the result hereinbefore stated.

We provide for doubling the line of stitching for a short distance at the beginning and ending of the sewing of the labels, where the beginning and ending of the stitching is at the same point on the label, by placing a grooved slide, as H , having a pawl H' pivoted to it, as at h'' , see Fig. 5, upon the top of the wheel G in such a manner that teeth g , see Figs. 1, 2, 6 and 7, will extend up into the groove h'' and hold the plate in place so that when the plate is drawn backward the point of the pawl H' will engage these teeth and draw the wheel G backward a short distance. This plate and pawl is held to normal position by means of any available form of spring, as indicated at H'' in Fig. 7, and may be drawn backward at the proper time, and the proper distance, by means of a cord, or other suitable device, as g' , secured at one end to the pawl H' in position to draw downward upon it, and at the other end to the shaft S , so that when the shaft is thrown suddenly back, as hereinbefore described, the sudden action of the cord g' upon the pawl H' will draw its point downward into engagement with the teeth g , and at the same time it will engage the upper corner of the pawl I' and move the pawl I' away from contact with the ratchet wheel G , and will draw the slide H , and with it, the wheel G , backward far enough so that the first three or four stitches in the label and fabric will be started back of the point where the last three or four stitches are sewed, thus greatly strengthening the sewing at this point and averting the danger of the labels becoming disconnected from the fabric at this point. h and h' represent stops that are secured to the yoke G' to hold the slide H to place on the wheel G , as indicated in Fig. 7.

The slot c'' in the actuating arm D must be made long enough to provide for all necessary longitudinal movement of the actuating lever, and of a proper width so that the antifriction roller c may move therein without danger of either becoming set so

that the arm can be moved only with difficulty, or of being so loose that the arm may vary from a direct movement.

The cord or cable T', shown in Figs. 1 and 3, is attached, at one end, to the end of the shaft S, and, passing over the antifriction roller or pulley T, it extends down to position where it may be actuated by the foot of the operator, by means of a treadle or otherwise, to draw the shaft S back to place to throw the belt R upon the driving pulley O' and start the machine, when desired.

While this attachment is made expressly for sewing on labels, tabs, &c., it is equally available for reinforcing a line of stitching, and for many other uses in general manufacturing business, all of which come within the intent of the invention.

20 What we claim as new, and desire to secure by Letters Patent of the United States, is:

1. In combination with a sewing machine, an attachment constructed with a base to be secured to the machine bed, an actuating arm slidably and pivotally mounted on said base, a plate secured to said actuating arm, a clamping plate pivotally secured to said plate, a spring for holding said clamping plate firmly against the first named plate, a form having inwardly projecting gear teeth, at the back end of the actuating arm, a gear wheel meshing with said gear teeth, a ratchet wheel and pawl for actuating said gear wheel, a cam and shaft beneath the machine bed, a slide actuated by said cam, an oscillating lever connected at one end with said slide, a connecting rod connecting the other end of said lever with the pawl, substantially as and for the purpose set forth.

2. In combination with a sewing machine and its bed and shuttle shaft, a base secured to the machine bed, a shaft mounted on said base and carrying a ratchet wheel and pawl and a gear wheel, a cam mounted on the shuttle shaft, a slide actuated by said cam, an oscillating lever actuated by said slide, a connecting rod connecting said lever with the pawl to actuate the ratchet wheel therefrom, an actuating arm mounted on the base, gear teeth formed at one end of the said arm in position to be engaged by the gear wheel, a forming block secured to the base, a guide at the end of the actuating arm to engage said block to guide the gear wheel in the form, a clamping plate secured to the actuating arm, an adjustable foot in said clamping plate formed to shape the desired lines of stitching, and means for actuating said clamping plate.

3. In combination with a sewing machine and its bed and shuttle shaft, a base secured to the bed of the machine, a movable pivotal

bearing on said base, an actuating arm mounted on said pivotal bearing in such a manner that it may be made to, at once, oscillate and move longitudinally thereon, and having an opening in one end with gear teeth projecting into said opening, a gear wheel to mesh with said teeth to actuate said arm, a clamping plate secured to the end of said arm, and having an opening through it in its line of travel under the needle, a supporting arm mounted on the base, a shaft mounted on said base and arm, a ratchet wheel and pawl and a gear wheel mounted on said shaft, a slide connected with and actuated by the shuttle shaft, an oscillating arm and connecting rod connecting said slide and the pawl to actuate the ratchet wheel, a sliding shaft mounted on the machine bed back of the base, a latch for locking said shaft to place, a spring for actuating said shaft when the latch is disconnected, a tight and loose pulley and a driving belt, a shifting arm on the said shaft for shifting the belt from the tight pulley to the loose pulley and back at the exact time that a given point on the plate approaches the needle, and means for drawing said shaft lengthwise against the spring, substantially as shown and described.

4. In combination with a sewing machine bed and shuttle shaft and the balance wheel and tight and loose pulleys for running a sewing machine, a base secured to the bed, an arm connected with said base, a shaft supported by said base and arm, a ratchet wheel and pawl, and a gear wheel mounted on said shaft, a slide connected with and actuated by the shuttle shaft, an oscillating lever and connecting rod actuated by said slide and actuating the pawl and ratchet wheel and shaft, an actuating arm actuated by the gear wheel on the ratchet shaft, clamping plates mounted on one end of said arm and arranged to be moved by said arm to sew stitches in various directions, means for opening and closing said clamping plates, a longitudinally movable shaft mounted back of the actuating arm, a shifting arm on said shaft, a belt on one of the pulleys arranged to be shifted from one to the other with the shifting arm at the exact time that a given point on the plate approaches the needle, a lever mounted on the machine in position so that the upper end comes in contact with the balance wheel, a shoulder on the balance wheel in position to be engaged by said lever, means for actuating said lever to suddenly stop the machine when the sliding shaft is moved to throw the belt upon the loose pulley, a spring for actuating the sliding shaft, a latch for holding it to position, and means for drawing the shaft to position under the latch substantially as shown and described.

5. In combination with a sewing machine and its bed and shuttle shaft a base secured to the bed of the machine, an arm mounted on said base, a shaft mounted on said base and arm, a ratchet wheel and pawl mounted on said shaft, an actuating arm and clamping plates mounted on the base and actuated by the shaft, means for actuating said ratchet wheel and shaft from the shuttle 10 shaft, a second set of ratchet teeth formed on the surface of the ratchet wheel, a sliding pawl mounted in position to be made to engage said teeth, and means for actuating said pawl to move the ratchet wheel and

shaft backward, and, also, to return it to 15 normal position, substantially as and for the purpose set forth.
